UNITED STATES PATENT OFFICE.

ALBERT W. MARTIN, OF INDIANAPOLIS, INDIANA.

FLUID-PRESSURE BELL RINGER.

Application filed March 25, 1921. Serial No. 455,519.

To all whom it may concern:

Be it known that I, ALBERT W. MARTIN, a citizen of the United States, and a resident of Indianapolis, county of Marion, and 5 State of Indiana, have invented a certain new and useful Fluid-Pressure Bell Ringer; and I do hereby declare that the following is a full, clear, and exact description thereof, reference being had to the accompanying 10 drawings, in which like numerals refer to like parts.

This invention relates to a bell construction wherein a bell is adapted to be rung by manual or fluid pressure means.

15 The chief object of the invention consists in the application of fluid pressure actuated means to the bell construction for ringing the same, said pressure means being associated with said bell construction in an improved manner to reduce the wear on the moving parts and also reduce the number of 20 moving parts.

The chief feature of the invention consists in positioning the pressure means for 25 ringing the bell adjacent the bell and associating the same directly with the clapper or ringing device, so that said clapper or ringing device will be directly actuated to ring the bell without tilting or rocking of 30 the bell.

Another feature of the invention consists in the arrangement of the several parts and the detailed construction thereof, whereby the bell yoke is pivotally supported and the 35 clapper is similarly supported.

The full nature of the invention will be understood from the accompanying drawings and the following description and claims.

40 In the drawings, Fig. 1 is a front elevational view of a bell construction embodying the invention and showing the general arrangement thereof. Fig. 2 is a side elevational view of the bell construction 45 shown in Fig. 1. Fig. 3 is a central cross sectional view of the fluid pressure means for ringing the bell. Fig. 4 is a central cross sectional view of the improved trunnion through which fluid pressure is transmitted to the fluid pressure means.

50 In the drawings, there is illustrated a conventional bell construction to which the invention has been applied. Said conventional bell construction is herein illustrated as 55 a locomotive bell construction wherein 10 indicates the base plate of a stand provided

with the upstanding arms 11 terminating in the bearings 12 and which are aligned to provide an axis upon which the bell is pivotally mounted. The bell is indicated by 60 the numeral 13, and there is also provided within the same a clapper or bell ringer 14 which may be of the usual or any preferred construction. A bell yoke 15 provided with a central support or collar 16 and two outwardly and aligned trunnions 17 pivotally support said bell in the bearings 12. One of the trunnions 17 is elongated and carries upon its projecting end a lever 18 by 65 which said bell may be rocked upon the axis 70 hereinbefore described by any suitable means such as a cord 19.

Heretofore the other trunnion 17 has been substantially similar to the first mentioned trunnion, and associated therewith was usually provided a pneumatic means, including an eccentric means upon said trunnion. Said pneumatic means, therefore, was adapted to tilt the bell construction upon the axis, as well as the lever 18. The present invention seeks to retain the feature of the pneumatic and automatic operation of the bell ringer, but to apply the same in such a manner that the bell does not have to be tilted upon its axis for ringing purposes, but may be otherwise actuated to ring the same. This object is accomplished by moving the clapper or bell ringing means adjacent the bell, thus eliminating the wear of the trunnions in the bearings. Heretofore, this wear has necessitated the replacement and repair of the bell construction since the operation of the eccentric means associated with the trunnion was dependent upon the perfect alignment of said trunnion in the bearing. 85

Heretofore the clapper or bell ringer 14 has been hingedly mounted adjacent and preferably within the bell, and this mounting is retained in the present construction. 100 In the present construction the clapper or ringer 14 is suspended by the pendulum strap or spring 20. The upper end of the pendulum strap is suitably secured to a rocker arm 21 which is pivotally supported on a pivot pin 22, which pivot pin in turn is supported by the ears 23 rigid with a supporting means, such as the cylinder 24. The bell is provided with a sleeve or hollow stem portion which is positioned within the central collar 110 portion 16 and is secured to and in said collar portion by suitable means such as the

nut 25. The clapper support 24 is provided with an upstanding spindle or stem 26, which also is secured within the sleeve portion of the bell construction and is concentric with 5 the same.

The fluid pressure means for tilting the clapper upon its pivotal support instead of tilting the bell upon its pivotal support comprises the cylinder housing 24 with the stem 26. The housing 24 is hollowed out to form a cylinder chamber 27, and in said cylinder chamber 27 is positioned a piston 28. One end of the cylinder chamber 27 is closed by suitable means such as the cap or closure member 29; while the other end of said cylinder is provided with an opening 30 which is closed by a guide or stem 31, which in the present instance is adapted to cooperate with the end wall and act as a valve 10 for the fluid pressure means. The piston 28 is provided with a discharge channel 32 extending from one end towards the other end and terminating in the guide or stem 31 in the port 33. Thus the port 33 for one 15 position of the piston is adapted to be uncovered and discharge into the atmosphere; for another position of the piston, it is adapted to be sealed; while for a third position of the piston, it communicates with the interior 20 of the cylinder. The guide stem or rod means 31 hereinbefore described is of less cross section area than the piston, and, therefore, the total pressure exerted upon the face of the piston adjacent said guide or stem 25 will only be less than that exerted upon the other face of the piston. The stem 26 is provided with an air supplying channel 34 which discharges into the cylinder 27 at or near the closed end of said cylinder. Thus, 30 fluid pressure admitted to the channel 34 is supplied to the cylinder and serves to move the piston shown in Fig. 3 to the right until such time as the port 33 is uncovered in the cylinder, whereupon said fluid pressure is transmitted to the opposite face of 35 the piston as well and the movement of said piston is then reversed, since the resultant pressure acting on the piston is proportional to the difference in the cross sectional areas 40 of the opposite faces. Thus, the piston will move towards the left until such time as the port 33 is uncovered and discharges into the atmosphere, whereupon the pressure is released from the larger face of the piston 45 and the pressure applied to the smaller face of the piston again reverses the movement of said piston from the left to the right.

The cylinder 24 is cut away at 35 preferably adjacent the ears 23. The piston is 50 also provided with a cut away portion 36 and a rocker arm 21 is extended at 37 so as to extend into and through the opening 35 in the cylinder and be seatable in the recess 36 of the piston so that said rocker arm will be 55 moved upon the axis of its pivot pin 22 by

the reciprocations of the piston 28 as hereinbefore described. Thus, the application of air pressure or any other fluid pressure to the conduit 34 serves to reciprocate or tilt the clapper or bell ringer 14 into engagement with the bell 13 to strike the same. 70

The means for supplying fluid pressure to the stem 26 provided with the conduit 34 includes suitable piping which may be of suitable material such as copper, said piping 75 38 being connected to the outwardly projecting stem 26 by suitable coupling means 39. A coupling 40, see Figs. 2 and 4, connects the other end of said piping or tubing to the apertured trunnion 17. In Fig. 4 the 80 improved trunnion is illustrated in detail and extending longitudinally through said trunnion, and herein illustrated as axially thereof, is a supply channel 41 which is enlarged at 42 to form a chamber to receive 85 suitable spring means 43 which is normally in engagement with the flange 44 of the pipe 45, which pipe 45 extends downwardly and is rigidly and non-rotatably supported in a bracket 46 upon the arm 11. A suitable 90 sleeve 47 has a threaded engagement with the enlargement or chamber 42, and as shown clearly in Fig. 4, said pipe 45 and said sleeve 47 are provided with complementary ground surfaces 48 to form a seal 95 or fluid-tight joint therebetween, which will nevertheless permit the pipe 45 to remain stationary but will permit the trunnion 17 to be rotated in the bearing 12 without loss of fluid pressure. It is to be noted that as 100 constructed, the spring 43 normally maintains the flange 44 in engagement with the sleeve 47, and that upon the application of fluid pressure to the conduit 45, said pressure serves to seal said two ground surfaces 105 so as to form a fluid-tight joint.

The pipe 45 is positioned axially of the trunnion 17, and from the foregoing it will be readily understood that the aforesaid construction permits the bell to be rung automatically by the fluid pressure means without tilting the bell upon its trunnion axis, yet will permit said bell to be rung by being tilted upon its trunnion axis by actuating the lever 18 or equivalent means. 110

While the invention has been described in great detail in the aforesaid specification, the same is to be considered as illustrative and not restrictive in character. In the aforesaid specification, a modification is 115 suggested, and this modification as well as others which will readily suggest themselves to those skilled in the art to which the aforesaid invention applies are all considered to be within the broad purview of the invention as outlined by the appended claims.

The invention claimed is:

1. In a bell construction the combination with a bell and bell striking means adjacent thereto, of a fluid pressure operable means 120

for actuating said bell striking means, comprising a longitudinally slotted cylinder, a piston slideable in said cylinder, and means mounted in the cylinder slot and movable by the reciprocation of said piston, said piston including a valve construction for controlling the reciprocations thereof.

2. A bell construction including a pivotally mounted bell, means for causing said bell to swing, a cylinder mounted within said bell, a reciprocating piston mounted in said cylinder, a striker pivotally mounted on said cylinder having one end thereof extending through said cylinder into engagement with said piston, and means for controlling the movement of said piston whereby said striker may be thereby held in position to be

engaged by the swinging of said bell or actuated by said piston for engaging said bell.

3. A bell construction including a pivotally mounted bell, a single bell striker contained within said bell, means for causing said bell to swing so as to engage said striker, and reciprocating means within said bell and movable therewith and connected with the striker for causing the same to be swung into engagement with said bell independently of the bell swing for ringing the same.

In witness whereof, I have hereunto affixed my signature.

ALBERT W. MARTIN.
